STROPPING DEVICE FOR SAFETY RAZOR
BLADES

Charles William Godson Little, deceased, late of Enfield, England, by Barclays Bank Limited, executor, London, England, assignor to Francis Stanley Lowe, Shiplake, Henley-on-Thames, England

Application October 20, 1942, Serial No. 462,761
In Great Britain October 30, 1941

2 Claims. (Cl. 51—153)

This invention comprises improvements in or relating to stropping devices for safety razor blades.

In the prior British Patent specification No. 421,738 there is described a device of this nature.

The principal object of the present invention is to provide an improved device embodying features which impart thereto a nice resilience during stropping while enabling a high reliability and efficiency of operation to be obtained and the construction to be simplified.

As will be realised the device is of somewhat similar construction to that described in the prior specification referred to but with the advantage that as the finger-held operating part is capable of resiliently yielding, it is possible to carry out the stropping with a nice feeling of resilience about the operation of the device. The resilience also makes for improved stropping as the pressure of the trailing edge of the blade on the strop is also of a desirably resilient nature.

A feature of the invention resides in making the finger-held operating part capable of resiliently yielding in a vertical direction, that is in a direction at right-angles to the direction in which the transverse movement takes place, when the device is first applied to a strop in order to position such part for leverage on the rocking device for the blade when the transverse movement takes place. This furthers the niceness of the feeling of resilience in using the device and gives desirably increased resilience in the stropping pressure.

In effect, the invention is thus able to provide what might be termed complete resilience of operation of the device and it will be appreciated that altogether it makes for rather pleasing and very reliable and efficient stropping. At the same time the construction can be very simple as the finger-held operating part may be a single member capable of yielding resiliently in vertical and horizontal manner.

Forms of the present invention will now be described by way of example and with reference to the accompanying drawing, wherein—

Figure 1 is a plan of one form shown partly in section, carrying a safety razor blade, and applied to a strop.

Figure 2 is a longitudinal vertical section thereof with parts shown in elevation.

Figure 3 is a section, on a larger scale than Figures 1 and 2, taken on the line III—III of Figure 2 and showing the blade rocked to bring its trailing edge into contact with the strop, and

Figure 4 is a longitudinal vertical sectional

view of a second form also on a larger scale than Figures 1 and 2.

According to Figures 1 to 3, the stropping device comprises a main body 1 bent to a closed hollow rectangular form in plan, Figure 1, and having a T form in elevation, Figure 2 (see also Figure 4 hereinafter described), the head of the T being constituted by lateral parts 2 which are bent as at 3 to a hollow rectangular shape, see Figure 3, to house the rocking device or lever hereinafter indicated. On this head of the main body is mounted a guard-frame 4 which is of substantially similar construction to that described in the aforesaid prior specification and is secured to the head 2, 3 by bent-out end portions 5 thereof which are perforated for the passage of lugs 6 provided on the head and bent over against the parts 5. The guard frame 4 which may be said to constitute an auxiliary body part of the device, is suitably contoured internally to the shape of the double-edged razor blade 7 as seen in Figure 1 and the blade is mounted in the frame in pivotal blade-gripping means 8 which is of similar construction, and receives the blade and is constructed to rock within said frame in a similar manner, to that described in the prior specification to which reference is directed for further details thereof. It need only be mentioned herein that the inner one of the trunnions 9 of the rockable blade-gripping means 8 is journaled in a bent-in portion 10 of one of the head parts 2 of the main body 1, see Figures 1 and 2 (also Figure 4), and has a rocking device in the form of a rocking lever 11 secured thereon within the head of the main body 1 just on the inner side of the part 10.

The rocking lever 11, Figures 1 to 3, is slotted at 12 for engagement by a projection 13 on the free end of a finger-held operating part 14. The finger-hold is provided by a hollow handle 15 which is closed at one end and at the open end, where it may be formed with outwardly bent lateral lugs 16 hereinafter referred to, is slidably fitted on to the part 14 and non-revolably secured thereon by forming it with diametrically-oppositely-disposed slots at 17 which are open at one end to pass over and engage the handle with wings 18 on the part 14. The finger-held operating part 14 is shown in the form of a flat blade which is of spring steel or other like material. It has the projection 13 and the wings 18 at one end, fits for the greater part of its length closely within the handle 15 to support the latter, and at the other end has a tail part formed with wings 19 which are engaged in slots

20 in lug parts 21 bent from the sides of the main body 1. From Figures 1 and 2, it will be seen that the wings 19 fit the slots 20 laterally but are capable of play in the longitudinal direction of the slots, while the extreme end of the tail part projects into a coil spring 22 which is placed under compression between such tail part and the adjacent end of the main body 1.

In the use of the stropping device shown in Figures 1 to 3, the device with the blade 7 mounted therein is taken by the handle 15 and placed with the guard-frame 4 flatwise, on a strop 23 and moved to and fro on the strop as indicated by the arrows in Figure 3. In thus applying the device to the strop there would, of course, be a natural tendency to exert downward pressure on the handle and it will be realised that the handle will be canted in a vertical plane under this pressure to a position such as is shown in Figure 2 in which its inner end is depressed. In the depressing movement, the finger-held operating part 14 inclines with the handle but the movement is only able to take place against the resilient action of the coil spring 22, the wings 19 moving longitudinally of the slots 20 of the main body during such movement and eventually coming to a stop against the opposite ends of the respective slots 20 to determine the amount of depression of the inner end of the handle as will be apparent from Figure 2. As a result of the depression of the inner end of the handle, the projection 13 on the part 14 is moved down to the bottom of the slot 12 of the rocking lever 11. Immediately, of course, the natural tendency is to move the device along the strop and in doing this the handle suitably cant horizontally and constrains the inner end of the part 14 to move with it owing to the engagement of the slots of the handle at 17 with the wings 18. The wings 19, however, at the tail end of the part 14 fit laterally in the slots 20. As a result, therefore, the part 14, can only yield resiliently with the horizontal cant of the handle. In this movement, which is an initial movement of the part 14 transversely in relation to the main body 1, the projection 13 rocks the rocking lever 11 and causes the blade to rock on its longitudinal axis about the trunnions 9 of the blade-gripping means 8, so as to bring the trailing edge of the blade on to the strop (see Figure 3) and cause it to be stropped during the ensuing movement of the stropping device along the strop. The resilience of the part 14 is such as to provide less resistance during horizontal canting of the handle 15 than does the friction between the strop and the guard-frame 4 and as a result, the blade is bound to be rocked to bring its trailing edge into contact with the strop before the device moves along the strop. As soon as the handle has initially canted horizontally with the resilience referred to and the blade has rocked as stated, the device commences to move along the strop. If desired the lugs 16 may be such as eventually to come, one or other, against the parts 5 of the guard-frame so as to assist in this movement of the device along the strop. The lugs 16 also form a convenient hold for the thumb and first finger of the hand on the handle 15. On return movement of the device along the strop the reverse actions take place as will be understood and when stropping is finished and the device removed from the strop the resilience of the part 14 and the action of the spring 22 cause the handle to be aligned with

the main body 1 as it was originally. The action is similar whether the device is used with one face or the other of the guard frame 4 in contact with the strop as will be understood.

5 In the form illustrated by Figure 4, wherein the guard-frame 4 and the blade 7 are broken away and the strop is not shown, the construction is very similar to that seen in Figures 1 to 3 and similar parts in the several figures are similarly numbered. However, in Figure 4, instead of using a coil spring for providing for resilience in the movement of the part 14 in the vertical plane, a flat or leaf form of spring 24 is used which is mounted on the outer end of the main body 1 by a bolt or screw 25 and has ends 26 bent into the path of movement of the wings 19 of the finger-held operating part 14. Also, instead of a lever form of rocking device 11, a cylindrical rocking device 27 is used which may have a vertical slot for engagement by the projection 13 on the finger-held operating part 14, or may be of sleeve form slotted at diametrically opposite points, one slot or the other being engaged by the projection 13 according to whether the stropping device is used with one face or the other of the guard frame 4 applied in contact with the strop. It is believed that the action of this form of device will be understood without further description.

10 20 25 30 35 In both forms of the stropping device thus described, the resilience makes for improved operation and improved stropping and there is a niceness of movement of the device and a cleanliness of stropping which will be highly appreciated by the keen shaver.

30 The spring 22 or 24 maintains the blade gripping means normally in its mid-position so that the blade lies within the guard frame and its edge will not come into contact with another object, for example the strop, and damage either itself or said object. The said spring also assists in the application of the correct pressure to ensure satisfactory stropping.

What is claimed is:

45 1. Device for stropping safety razor blades, comprising a body, a blade holder pivotally mounted upon said body in such manner as to be capable of rocking about its longitudinal axis, a rocking device connected to said blade holder, a finger-held operating part of spring blade form having one end in operative relation with said rocking device, means for mounting said part by its other end in said body in such manner that said one end is capable of resiliently yielding in a direction at right-angles to the plane of said part and said part is capable of moving in said plane to engage with said rocking device on one or the opposite side of the pivotal axis of said rocking device, and a spring mounted to be operative between said body and said part on said moving of said part in said plane so that such moving takes place against resistance of said spring.

50 55 60 65 70 75 2. Stropping device according to claim 1, and further comprising a hollow handle fitted to the finger-held operating part in engagement with the opposite longitudinal edge portions of such part, said handle and edge portions being positively engaged with one another so that the handle is non-revolvable with respect to said part.
